UNITED STATES PATENT OFFICE.

DAVID G. DAVIES, OF SPOKANE, WASHINGTON.

LIQUID-LEVEL INDICATOR.

1,029,598.

Specification of Letters Patent. Patented June 18, 1912.

Application filed April 28, 1911. Serial No. 623,840.

To all whom it may concern:

Be it known that I, DAVID G. DAVIES, a citizen of the United States, residing at Spokane, in the county of Spokane and State of Washington, have invented a new and useful Liquid-Level Indicator, of which the following is a specification.

This invention relates to an improvement in liquid level indicators, the primary object of the invention being the provision of a liquid level indicator, whereby the rise or fall of the liquid in a tank or reservoir, will operate by pressure, either in a direction toward or away, to make an electrical connection of varying resistance, according to the distance of such rise or fall, to operate a calibrated indicator, giving the condition minutely, and simultaneously setting off an alarm.

20 A further object of the present invention is the employment of a conducting conduit which by reason of the rise or fall of the water, permits either the action of pressure or vacuum, caused by the pressure of the 25 water in the conduit or the suction power of the water therein, to operate electrical circuit makers, which are graduated through a resistance coil to a calibrated indicator, whereby the slightest variation in the rise 30 or fall is accurately indicated, and an alarm given.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within 40 the scope of what is claimed without departing from the spirit of the invention.

In the drawings:—Figure 1 is a section view through a portion of a tank or reservoir with the preferred form of the invention in operative relation thereto, the electrical circuits being shown in diagram. Fig. 2 is a similar view showing a modified form of circuit making means.

Referring to the drawings, and more particularly to Fig. 1, thereof, the reservoir or tank, A, which contains the liquid, has mounted therein a pipe 2, at whose lower end is provided the inverted dome 1, which is provided with inlet openings a, in its lower edges, and therefore permitting water or liquid in the reservoir to enter the pipe

2 and seek its level therein. Above the level of the water in the pipe 2, and trapped in the casing 3, by means of the cover 4, is air, so that any rise of the water or liquid in the 60 reservoir will cause a corresponding rise in the pipe 2, and produce an increase in the air pressure in the casing 3, which pressure will cause the center of the flexible cover 4 to rise. The spring 5, normally pulls the 65 center of the cover 4 downwardly, so that the mercury in the cup 6, is normally held out of contact with the series of contact fingers 7, carried by the disk 8, disposed directly above and in line with the mercury 70 cup 6. The shortest fingers 7, indicate "High" water mark, while the longest fingers 7, indicate "Low" water mark, the intermediate fingers 7, indicating the intermediate levels. It will thus be seen that any 75 rise of the fluid in the reservoir will produce an air pressure within the chamber or casing 3, raising the flexible cover 4 and its mercury bowl 6, whose mercury engaging the "Low" water finger 7, first will close a 80 circuit herein after described to gradually indicate the rise of the water, or fluid in the reservoir, until the shortest or "High" water finger 7, is immersed in the mercury, during which time the galvanometer or indicator 85 15, which is of a low potential, but high resistance, is operated, through the wire 9, the graduated resistance coil 10, wire 11, dry batteries 12, positive wire 13, and variable resistance 14. The return is through 90 the neutral wire 16, armature 17, of the relay 18, and wire 19 to the cover 4 and mercury cup 6. The alarm 20 may also be used, it being connected in circuit with the indicator as shown.

In connection with the "Low" water alarm, it will be necessary to use a local relay circuit 21, in which at low water, the relay circuit is opened, the relay magnets are deenergized, and consequently the 100 alarm circuit closed giving the alarm.

The apparatus as shown in Fig. 2, is especially adapted for low water reservoirs and the tube or pipe 2', is provided with an up-turned lower end 1', while the upper end 105 is curved downwardly to provide a vacuum chamber 2'', above the top of the reservoir or tank A'. The outlet end of the tube or pipe terminates in the receptacle 22, which contains mercury, which is in contact with 110 the graduated contact fingers 7', which as before described are carried by the disk 8', to

which is connected the usual circuits for actuating the indicator 15' and indicator 20'. The action of this apparatus, is by vacuum, within the tube or pipe 2', instead of by pressure as in the first instance, the fall of the water within the reservoir A', drawing the air into the tube 2', and downwardly therein, such action causing the mercury within the receptacle 22, to be drawn within 5 the end of the tube adjacent to the said receptacle, and reducing the level of the mercury in the said receptacle, this action effecting the contacts 7', in rotation until the indicator indicates "Low" water. The filling 10 of the reservoir has the reverse effect, causing the mercury to rise and while gradually rising operate the indicator to indicate the rise of the water within the reservoir A', and until the "High" water is indicated 15 20 and the shortest finger 7' is contacted by the mercury.

What is claimed, is:—

1. In an apparatus of this character, the combination with a reservoir containing liquid, a source of electrical energy, and an electrically operated indicator to indicate the fluctuations of the liquid level within the reservoir, of means for actuating said electrically operated indicator through the 25 source of electrical energy, comprising a tube extending above the water level mounted to have liquid rise therein to seek the level of the liquid in the reservoir, a receptacle containing a liquid circuit maker operably connected with the outer end of said tube, and a series of co-acting contacts adapted to 30 35 co-act with the liquid circuit maker to operate the indicator.
2. In an apparatus of this character, the combination with a reservoir containing liquid, a source of electrical energy, and an electrically operated indicator to indicate the fluctuations of the liquid level within the reservoir, of means for actuating said 40 45 indicator by forming electrical circuits, comprising a tube mounted in the reservoir and having an open end to permit the liquid to seek its level in the tube, the upper end of the tube being above the reservoir, a receptacle containing a liquid circuit maker operably connected with the upper end of the tube, and a series of contacts of graduated 50 55 lengths positioned to co-act with the liquid circuit maker to operate the indicator.
3. In an apparatus of this character, the

combination with a reservoir, a source of electrical energy, and an electrically operated indicator to indicate the fluctuations of the liquid levels in the reservoir, of a tube having its lower end open and immersed in the reservoir to permit the liquid in the reservoir to seek its level in the tube, the upper end of said tube extending above and exterior of the reservoir, a receptacle containing a liquid circuit maker operably connected with the upper end of said tube, said liquid being actuated by the fluctuations of the liquid level within the tube, and a series of different length contacts disposed above to co-act with the liquid circuit maker to complete electrical circuits and operate the indicator. 60 65 70

4. In an apparatus of this character, the combination with a reservoir, a source of electrical energy, and an electrically operated indicator to indicate the fluctuations of the liquid levels in the reservoir, a tube having a lower open end immersed in the liquid of the reservoir and having its upper end projecting above the water level and exteriorly of the reservoir, a liquid circuit maker operably connected to the upper end of said tube and actuated by the fluctuations of the liquid level of the reservoir through said tube, and a series of graduated contacts disposed above to co-act with the said liquid circuit maker to make electrical circuits to operate the indicator. 75 80 85

5. In an apparatus of this character, the combination with a reservoir, a source of electrical energy, and an electrically operated indicator to indicate the fluctuations of the liquid levels in the reservoir, a tube having a lower open end immersed in the reservoir and having its upper end projecting above the reservoir, a reservoir provided with a spring tensioned cover in communication with the upper end of the tube, a receptacle containing a liquid circuit maker carried by said cover, and a series of contacts adapted to co-act with the liquid circuit maker to form electrical circuits to operate the indicator. 90 95 100

In testimony that I claim the foregoing as my own, I have hereto affixed my signature in the presence of two witnesses.

DAVID G. DAVIES.
